MOISTENING DEVICE FOR DUPLICATING MACHINES

Egidio Maria Benello, New York, N. Y.

Application April 29, 1937, Serial No. 139,695
Renewed September 23, 1938

17 Claims. (Cl. 101—132)

The present invention relates to duplicating machines of the type in which a clear sheet previously moistened with a readily volatilizing solvent is printed onto by means of a copyable mirror-script original, and, more particularly, to a novel and improved moistening device for duplicating machines of the described character.

As those skilled in the art know, in duplicating machines of this type it was of very great importance to provide a thin film or coating of a readily volatilizing solvent and having an extremely uniform and well balanced character on the copy sheet to be printed onto since the number of copies obtainable and the quality of the copies largely depended on the uniform and positively controlled character of the solvent film. Insufficient amounts of solvent caused the printing of weak and imperfect copies, excessive amounts of solvent used up the ink of the copyable original very rapidly and reduced the number of copies obtainable from a single original. Irregular distribution of the solvent on the surface of the copy sheet had the disadvantage of using up different quantities of the ink on different portions of the original, so that after printing a few imperfect copies the uniformity of the original was destroyed and the printing of perfect copies was rendered impossible even if the distribution of the solvent has been subsequently corrected. Clearly, the art was faced with a complex problem of the utmost importance for which, as far as I am aware, no complete and simple solution was available.

I have discovered that the problem may be solved in a remarkably simple manner.

It is an object of the present invention to provide a moistening device for duplicating machines which is substantially free from the disadvantages and inconveniences of prior and conventional moistening devices.

It is another object of the present invention to provide a novel and improved moistening device for duplicating machines including a pair of combination feed and moistening rollers adapted to deposit a uniform and delicately balanced film or coating of a readily volatilizing solvent on a copy sheet and in which the solvent is supplied to the said moistening rollers in a fool-proof and positively controlled manner.

It is a further object of the invention to provide a moistening device of novel and improved character in which fine jets or sprays of a readily volatilizing solvent are directed against a moistening roller of suitable character which transfers and deposits this solvent on the copy sheet in the form of a completely uniform film or coating.

The invention also contemplates the provision of a moistening device for duplicating machines which may be readily installed in conventional

duplicating machines of the mirror-script type without excessive cost or difficulty and which thus permits converting an old and imperfect machine into a machine of novel and of highly improved character.

It is also within the contemplation of the invention to provide a moistening device for duplicating machines adapted to dispense a readily volatilizing solvent, which is simple in construction and easy and inexpensive to manufacture and to operate.

Other and further objects and advantages of the present invention will become apparent from the present description taken in conjunction with the accompanying drawing, in which

Fig. 1 is a diagrammatic view, somewhat fragmentary, of a duplicating machine embodying the principles of the present invention;

Fig. 2 depicts a side elevational detail view, also fragmentary, illustrating the moistening rollers 20 and the solvent distributing or spray tube.

Broadly stated, according to the principles of my invention, I provide a printing roller and a counter pressure roller co-operating with each other in conventional manner. The printing roller is provided with means for receiving and holding a copyable mirror-script original which may be copied onto a clear sheet previously moistened with a readily volatilizing solvent and introduced in between the printing and counter pressure rollers. In front of the bight of said rollers I provide a pair of combination feed and moistening rollers. These rollers have a double object. First of all, they are provided with suitable driving means to be rotated in conformity with the rotation of the printing roller so that a copy sheet introduced in between the bight of said feed and moistening rollers is automatically fed at the correct speed and special arrangement to the printing and counter pressure rollers. In addition to this, these rollers are also employed to apply and to impress a thin and uniform film or coating of solvent onto the copy sheet. I have discovered that excellent results are obtained by feeding the solvent in the form of a plurality of fine jets or sprays against the circumferential surface of the upper or moistening roller proper, while the lower one of the feed rollers acts as a counter moistening roller and presses the clear sheet against the moistening roller. Preferably, a pipe or tube is arranged in parallel spaced relation with the moistening roller and is provided with a row of fine holes. This solvent spraying or distributing pipe is connected to a solvent reservoir from which the solvent may be fed to the distributor or spray tube by means of a small pump. I have found it advantageous to actuate this small pump directly by means of a suitable rotating or reciprocating part of the duplicating machine, such as, for example, the duplicating or

printing roller, so that a definite and predetermined amount is fed for each revolution of the machine and thus for the printing of each copy sheet. This type of construction correctly and accurately adjusts the supplied amount of the moistening solvent to the operation of the machine so that the dangers of both insufficient and of excessive moistening are effectively prevented. Preferably, the moistening roller is constituted of a slightly elastic and microporous material, such as for example, rubber. Particularly good results are obtained with moistening rollers constituted of various synthetic rubbers now obtainable on the market, since these materials are not affected by the chemical action of the solvent. The lower or counter moistening roller is preferably constituted of a rigid and highly polished material such as, for example, brass, a nickel-copper alloy sold on the market under the trademark "Monel" metal or of a suitable synthetic resin. The highly polished surface has the advantage that it is easily wiped off and is left dry by means of a suitable pad or wiper bearing against the surface thereof. The counter moistening roller may be provided with an entirely smooth circumferential surface, preferably, however, its surface is provided with fine spirally or concentrically arranged grooves in order to facilitate the removal of excess moisture from the surface thereof.

The invention will now be more fully described to those skilled in the art reference being had to the accompanying drawing illustrating by way of example a practical and preferred embodiment of the present invention.

A printing roller 1 and a counter pressure roller 2 are provided in parallel spaced and cooperating relation. In view of the conventional character of this arrangement, driving means and supporting means for these rollers have been omitted for the sake of simplicity. In front of the bight of these rollers are provided combination feed and moistening rollers 3 and 4. Rollers 3 and 4 are adapted to be rotated in conformity with the rotation of the printing and counter pressure rollers in conventional manner. Copy sheets to be printed onto may be introduced in between the cooperating rollers by means of a feed table 5, the printed copies being deposited on a receiving tray 6. Above moistening roller 3 and in parallel spaced relation therewith is arranged a horizontal spray tube 8 having a large number of fine holes or spraying nozzles 8-1 arranged along the length thereof in a single or in a plurality of rows. A conduit 9 connects spray tube 8 to a solvent reservoir 12 located at a lower level than the spray tube. Solvent reservoir 12 has a filling cap 13 through which it may be replenished with a suitable readily volatilizing solvent and is associated with a small pump 14. Pump 14 essentially comprises a piston 15 and shaft 16 adapted to be reciprocated within the pump. Simple intake and outlet valves in the form of small balls 17 and 18, respectively, are provided in the lower portion of the pump in suitable and conventional seats so that reciprocation of the piston in the pump will cause solvent to be pumped and to be supplied to spray tube 8. Moistening roller 3 and spray tube 8 are provided with a suitable shield or cover 10 which protects the surface of the roller from interference and dust. The lower portion of shield 10 is provided with a removable part 11 secured to the shield and holding a strip 75 of felt 7. This strip of felt has the object of fur-

ther distributing the solvent sprayed on the circumference of the moistening roller and of absorbing excess moisture. Counter moistening roller 4 is provided with a plurality of fine grooves, 4-1.

Pump 14 may be actuated in any suitable manner by means of a rotating or reciprocating part of the duplicating machine. It is generally preferred to actuate the pump directly by or in conformity with the rotation of the printing roller. For example, a suitable cam may be mounted on one of the sides of the printing roller which will actuate a lever mechanism once or several times during each revolution of the printing roller and will cause one or several pumping strokes of the pump for each revolution of the printing roller. An arrangement of this character is shown in Fig. 1, in which a cam 19 is secured to one of the sides of the printing roller. A small roller 20 mounted at one end of a spring-held lever 21 is bearing against the surface of cam 19 and is displaced around a pivot 22 during rotation of the printing roller. The other end of lever 21 is slotted and is provided with a slotted extension piece 23 which permits adjusting the length of the lever arm and which may be fastened in any position by means of screws 24. To the outer end of the extension piece 23 is connected a rod 26 which is jointedly connected to piston shaft 16. Rod 26 is constituted of two parts which are adjustably connected to each other by means of a nut 27 which at the same time permits adjustment of the length of the rod.

From the preceding description, the operation of my improved moistening device will be readily understood by those skilled in the art. A clear sheet to be printed onto is introduced in between the bight of combination feed and moistening rollers 3 and 4 and hereafter the driving means for rollers 1, 2, 3 and 4 are actuated. Each rotation of printing roller 1 will cause rotation of cam 19 which will lift up lever 21 and will tension spring 25 at the same time downwardly displacing piston 15 of pump 14 so that a predetermined and positively controlled amount of readily volatilizing solvent will be forced through conduit 9 into spray tube 8. Spray tube 8 will spray this unitary quantity of solvent onto the surface of moistening roller 3. After the cam passed roller 20, spring 25 will return lever 21 into its normal position of rest and prepares the pump for the next stroke. It will be noted that the length of the stroke and thereby the unitary quantity of solvent pumped for each revolution of the printing roller can be adjusted by means of the displaceable extension piece 23, or by means of nut 27, as those skilled in the art will readily understand. Wiper 7, bearing against the surface of moistening roller 3 will further distribute this moisture on the surface of the moistening roller so that a completely uniform and regular film of the readily volatilizing solvent will be applied to the face of the copy sheet.

It is to be noted that the moistening device embodying the principles of the present invention provides a number of important advantages. First of all, a uniform and positively controlled amount of solvent is applied to the surface of the copy sheet in a simple and efficient manner and both insufficient moistening and excessive moistening of the copy sheets are prevented.

It is also to be observed that the same predetermined and adjustable amount of solvent is fed for each copy sheet irrespective of the operating speed of the machine. The copy sheet is 75

moistened completely and with great accuracy without leaving any unmoistened marginal edges which cannot be printed onto.

Moreover, my improved moistening device is extremely simple and inexpensive to manufacture and to operate and is very economical in the use of the solvent.

Although the present invention has been described in connection with a preferred embodiment thereof, variations and modifications may be resorted to by those skilled in the art without departing from the principles of the present invention. I consider all of these variations and modifications as within the true spirit and scope of the present invention as disclosed in the present description and defined by the appended claims.

I claim:—

1. In a duplicating machine for printing onto clear sheets previously moistened with a readily volatilizing solvent matter imprinted in copyable mirror-script on a master sheet, a moistening device for said sheet, said moistening device comprising in combination a moistening roller, a counter moistening roller cooperating therewith, and means for applying a fine spray of a readily volatilizing solvent onto the surface of said moistening roller for moistening said clear sheets.

2. In a duplicating machine for printing onto clear sheets previously moistened with a readily volatilizing solvent matter imprinted in copyable mirror-script on a master sheet, a moistening device for said sheet, said moistening device comprising in combination a moistening roller, a counter moistening roller cooperating therewith, spraying means for spraying a readily volatilizing solvent onto the circumferential surface of said moistening roller, and means for feeding solvent to said spraying means.

3. In a duplicating machine for printing onto clear sheets previously moistened with a readily volatilizing solvent matter imprinted in copyable mirror-script on a master sheet secured around the circumference of a printing roller, a moistening device for said sheet, said moistening device comprising in combination a moistening roller, a counter moistening roller cooperating therewith, means for spraying a readily volatilizing solvent onto the circumferential surface of said moistening roller, means for feeding said solvent to said spraying means, and means for controlling said feeding means in accordance with the operation of said printing roller.

4. In a duplicating machine for printing onto clear sheets previously moistened with a readily volatilizing solvent matter imprinted in copyable mirror-script on a master sheet, a moistening device for said sheet, said moistening device comprising in combination a moistening roller, a counter moistening roller cooperating therewith, means for applying a finely distributed spray of a readily volatilizing solvent onto the circumferential surface of said moistening roller, and means for feeding a predetermined amount of said solvent to said spraying means for each clear sheet to be printed onto.

5. In a duplicating machine for printing onto clear sheets previously moistened with a readily volatilizing solvent matter imprinted in copyable mirror-script on a master sheet, a moistening device for said sheet, said moistening device comprising in combination a moistening roller, a counter moistening roller cooperating therewith, means for spraying a finely distributed and readily volatilizing solvent onto the circumferential

surface of said moistening roller, means for feeding a predetermined unitary amount of said solvent for each clear sheet to be printed onto, and means for adjusting said feeding means to vary said unitary amounts.

6. In a duplicating machine for printing onto clear sheets previously moistened with a readily volatilizing solvent matter imprinted in copyable mirror-script on a master sheet secured around the circumference of a printing roller, a moistening device for said sheet, said moistening device comprising in combination a moistening roller, a counter moistening roller cooperating therewith, means for spraying finely distributed and readily volatilizing solvent onto said moistening roller, means for uniformly distributing said sprayed solvent on the circumferential surface of said moistening roller, and means intermittently actuated by said printing roller for feeding a predetermined amount of said solvent to said spraying means for each rotation of said printing roller.

7. In a duplicating machine for printing onto clear sheets previously moistened with a readily volatilizing solvent matter imprinted in copyable mirror-script on a master sheet, a moistening device for said sheet, said moistening device comprising in combination a moistening roller, a counter moistening roller cooperating therewith, means for spraying finely distributed and readily volatilizing solvent onto said moistening roller, means for uniformly distributing said sprayed solvent on the circumferential surface of said moistening roller, a reservoir for said solvent, and means for supplying solvent from said reservoir to said spraying means.

8. In a duplicating machine for printing onto clear sheets previously moistened with a readily volatilizing solvent matter imprinted in copyable mirror-script on a master sheet secured around the circumference of a printing roller, a moistening device for said sheet, said moistening device comprising in combination a moistening roller, a counter moistening roller cooperating therewith, means for spraying finely distributed and readily volatilizing solvent onto said moistening roller, means for uniformly distributing said sprayed solvent on the circumferential surface of said moistening roller, a reservoir for said solvent, conduit means intermediate to said reservoir and said spraying means, and means intermittently actuated by said printing roller for forcing a unitary amount of said solvent into said spraying means for each rotation of said printing roller.

9. In a duplicating machine for printing onto clear sheets previously moistened with a readily volatilizing solvent matter imprinted in copyable mirror-script on a master sheet, a moistening device for said sheet, said moistening device comprising in combination a moistening roller, a counter moistening roller cooperating therewith, means for spraying finely distributed and readily volatilizing solvent onto said moistening roller, means including a felt pad for uniformly distributing said sprayed solvent on the circumferential surface of said moistening roller, a reservoir for said solvent and located at a lower level than said spraying means, conduit means intermediate to said reservoir and said spraying means, and pumping means for intermittently feeding solvent from said reservoir to said spraying means.

10. In a duplicating machine for printing onto clear sheets previously moistened with a readily

- 5 volatilizing solvent matter imprinted in copyable
mirror-script on a master sheet, a moistening device for said sheet, said moistening device comprising in combination a moistening roller con-
stituted of an elastic and microporous material, a
counter moistening roller constituted of a highly
polished rigid material cooperating with said
moistening roller, means for spraying finely dis-
tributed and readily volatilizing solvent onto said
10 moistening roller, means including a felt pad for
uniformly-distributing said sprayed solvent on the
circumferential surface of said moistening roller,
a reservoir for said solvent and located at a lower
level than said spraying means, conduit means
15 intermediate to said reservoir and said spraying
means, and pumping means for intermittently
feeding solvent from said reservoir to said spraying
means.
11. In a duplicating machine for printing onto
20 clear sheets previously moistened with a readily
volatilizing solvent matter imprinted in copyable
mirror-script on a master sheet, a moistening device for said sheet, said moistening device comprising in combination a moistening roller con-
stituted of synthetic rubber, a counter moistening
25 roller constituted of a highly polished material
and having uniformly distributed fine grooves
thereon cooperating with said moistening roller,
means for spraying finely distributed and readily
30 volatilizing solvent onto said moistening roller,
means including a felt pad for uniformly dis-
tributing said sprayed solvent on the circumferential
surface of said moistening roller, a reservoir for
35 said solvent and located at a lower level than
said spraying means, conduit means intermediate
to said reservoir and said spraying means, and
pumping means for intermittently feeding solvent
from said reservoir to said spraying means.
12. In a duplicating machine for printing onto
40 clear sheets previously moistened with a readily
volatilizing solvent matter imprinted in copyable
mirror-script on a master sheet, a moistening device for said sheet, said moistening device comprising in combination a moistening roller, a
45 counter moistening roller cooperating therewith,
and a spray tube extending along the length of
said moistening roller for applying a finely dis-
tributed spray of a readily volatilizing solvent
onto the circumferential surface of said moisten-
50 ing roller for moistening said sheets.
13. In a duplicating machine for printing onto
clear sheets previously moistened with a readily
volatilizing solvent matter imprinted in copyable
mirror-script on a master sheet, a moistening
55 device for said sheet, said moistening device comprising in combination a moistening roller, a
counter moistening roller cooperating therewith, a
spray tube having a plurality of fine holes therein
arranged in parallel spaced relationship with said
60 moistening roller, and means for supplying a
readily volatilizing solvent to said spray tube.
14. In a duplicating machine for printing onto
clear sheets previously moistened with a readily
volatilizing solvent matter imprinted in copyable
65 mirror-script on a master sheet, a moistening device for said sheet, said moistening device comprising in combination a moistening roller, a
counter moistening roller cooperating therewith,
a substantially horizontal spray tube having a
70 plurality of fine holes uniformly distributed along
the length thereof for applying a finely distributed
spray of a readily volatilizing solvent onto the
circumferential surface of said moistening roller,
- 5 a felt pad bearing against the surface of said moist-
tening roller for distributing said spray, a reser-
voir for said solvent, conduit means intermediate
to said reservoir and said spray tube, and a pump
for feeding said solvent to said spray tube.
- 10 15. In a duplicating machine for printing onto
clear sheets previously moistened with a readily
volatilizing solvent matter imprinted in copyable
mirror-script on a master sheet secured around
the circumference of a printing roller, a moisten-
15 ing device for said sheet, said moistening device
comprising in combination a moistening roller, a
counter moistening roller cooperating therewith,
a substantially horizontal spray tube having a
plurality of nozzles uniformly distributed along
20 the length thereof for applying a fine spray of a
readily volatilizing solvent onto the circumferential
surface of said moistening roller, a felt pad
bearing against the surface of said moistening
25 roller to distribute said spray thereon, a reservoir
for said solvent, conduit means intermediate said
reservoir and said spray tube, a pump for feeding
said solvent from said reservoir to said spray tube,
and means including a cam for actuating said
30 pump in accordance with the rotation of said
printing roller.
- 35 16. In a duplicating machine for printing onto
clear sheets previously moistened with a readily
volatilizing solvent matter imprinted in copyable
mirror-script on a master sheet secured around
the circumference of a printing roller, a moisten-
40 ing device for said sheet, said moistening device
comprising in combination a moistening roller, a
counter moistening roller cooperating therewith,
a spray tube having a plurality of openings uni-
formly distributed along the length thereof for
45 applying a fine spray of a readily volatilizing sol-
vent onto the circumferential surface of said moisten-
ing roller, a felt pad bearing against said moisten-
ing roller to distribute said spray thereon, a
50 reservoir for said solvent, conduit means inter-
mediate to said reservoir and said spray tube, a
pump for feeding said solvent from said reservoir
to said spray tube, means including a cam and a
lever mechanism for actuating said pump by the
55 rotation of said printing roller, and means for
adjusting the stroke of said pump to control the
amount of solvent fed to said spray tube for each
rotation of said printing roller.
- 60 17. In a duplicating machine for printing onto
clear sheets previously moistened with a readily
volatilizing solvent imprinted in copyable mirror-
script on a master sheet secured around the cir-
cumference of a printing roller, a moistening de-
65 vice for said sheet, said moistening device com-
prising in combination a moistening roller, a
counter moistening roller cooperating therewith,
a spray tube having a plurality of openings uni-
formly distributed along the length thereof for
70 applying a fine spray of a readily volatilizing sol-
vent onto the circumferential surface of said moisten-
ing roller, a felt pad bearing against said moisten-
ing roller to distribute said spray thereon, a
75 reservoir for said solvent, conduit means inter-
mediate to said reservoir and said spray tube, a
pump for feeding said solvent from said reservoir
to said spray tube, a cam connected to one side of
80 said printing roller, a lever mechanism and an
actuating rod cooperating with said cam for actu-
ating said pump, and means for varying the effec-
tive length of said lever and of said rod for
adjusting the stroke of said pump.

EGIDIO MARIA BENELLO.
